UNITED STATES PATENT OFFICE.

JAMES J. WOOD, OF FORT WAYNE, INDIANA, ASSIGNOR TO GENERAL ELECTRIC COMPANY, A CORPORATION OF NEW YORK.

MOTOR-DRIVE.

1,206,634.

Specification of Letters Patent. Patented Nov. 28, 1916.

Application filed September 2, 1915. Serial No. 48,719.

To all whom it may concern:

Be it known that I, JAMES J. WOOD, a citizen of the United States, residing at Fort Wayne, in the county of Allen, State of Indiana, have invented certain new and useful 5 Improvements in Motor-Drives, of which the following is a specification.

My invention relates to motor drives and is particularly applicable to electric motor 10 drives for sewing machines and the like.

My invention has for its object a novel arrangement and construction of such an electric motor drive in which the electric motor is controlled by a switch and a friction brake 15 with a single actuating member for the switch and brake which closes the switch to complete the motor circuit and progressively decreases the effectiveness of the brake.

The various features of novelty which 20 characterize my invention are pointed out with particularity in the claims annexed to and forming a part of this specification.

For a better understanding of my invention reference may be had to the following 25 description taken in connection with the accompanying drawings, in which—

Figure 1 is a view of a sewing machine equipped with an electric motor drive in accordance with my invention; Figs. 2 and 3 30 are side views of the motor of Fig. 1; Fig. 4 is a sectional view on the line 4—4 of Fig. 2; Fig. 5 is a side view of one end of the motor, and Fig. 6 is a view of a detail.

In Fig. 1 of the drawings, 1 is the supporting stand of the machine on the top of which is mounted the usual table 2. In this table is countersunk the bed-plate 3 of the sewing machine. The head of the sewing machine is mounted on the bed-plate 3 and 35 consists of the usual pillar 4, horizontal arm, fly-wheel 5 and drive wheel 6, and contains the usual mechanism for transmitting motion from the drive wheel 6 to the needle bar. The bed-plate 3 contains the usual shuttle 40 and feed mechanism and means for transmitting motion thereto through the pillar and drive-wheel. The ordinary foot power mechanism is mounted in the stand 1 and consists of a pivoted treadle 7 adapted to 45 transmit power through a connecting rod 8 to a crank 9 of the main driving wheel 10. For foot operation, power is transmitted from the main driving wheel 10 to the driving wheel 6 through a belt 11. The motor 50 drive for the machine consists of an electric

motor 12 attached to the bed-plate 3 in any suitable manner, as by means of lugs or brackets 13 on the motor frame and bolts which pass through hollow spacing posts 14. These parts may be of any well known or 60 usual construction.

The mechanism for controlling the motor is shown in detail in Figs. 2 to 6. The motor is controlled by a friction brake 15 and switch 16, both of which are actuated by a 65 slide 17. The slide 17 has a slot and pin connection with the motor frame and is adapted to move in substantially a straight line. A brake lever 18 is operatively connected with the brake 15 and the slide 70 17 and is preferably pivoted on the motor frame, the pivot being mounted in projecting lugs 19 which are shown as being cast integral with the frame. The connection between the brake lever and the slide is 75 preferably also a slot and pin one. If the slide 17 is moved downwardly from the normal position shown in the drawings by means of a cord or chain 20, it first closes the switch 16 and then progressively decreases the effectiveness of the brake 15 on the motor, permitting the motor to run at any speed desired up to its maximum. The chain 20 may be connected to a hook 21 on the treadle 7. A spring 22 engages the brake 80 lever 18 and acts in a direction to apply the brake. A second spring 23 is operatively associated with the slide 17 and acts in a direction to normally maintain the slide in the 85 position in which the switch 16 is open and the brake 15 applied.

The brake 15 preferably comprises stationary and rotatable friction plates surrounding the shaft 24 of the motor. The stationary plates 25 may be made of fiber. 90 The outer rotatable plate 27 is fastened to the shaft of the motor. The rotatable plate 28 is placed between the two stationary plates 25 and is connected to the outer rotatable plate 27 by a dowel pin 29. The plate 100 28 is split as shown in Fig. 6 to make it act as a spring so that the brake will not grip too quickly. The inner plate 30 has a hub 31 which surrounds one of the bearings for the motor shaft and is prevented from rotating by a pin 32 which engages a slot in the hub 31. The stationary plates 25 have projecting lugs which engage pins 26 mounted on the inner plate 30. The end 33 of the 105 brake lever is bifurcated and straddles the 110

shaft 24. This end of the brake lever normally engages the stationary friction plate 30. The other end 34 of the brake lever has a pin 35 which engages the slot 36 in the 5 slide 17. The slide has a second slot 37 which engages a pin 38 mounted on the motor frame. The spring 23 has one end connected to the slide and the other end is connected to the motor frame by means of a 10 member 39 on the pin 38.

The switch 16 comprises two stationary contacts 40, and a movable contact 41 which is arranged to bridge the stationary contacts and thereby complete the motor circuit. 15 The movable contact 41 is carried on the end of a switch arm 42 pivoted on the pin 38. A spring 43 is connected at one end to the free end of the switch arm 42 and at the other end to the slide 17. All of the control 20 mechanism is mounted on the motor frame so that when the motor is fastened to the bed-plate as described above, with its pulley 44 connected to the fly-wheel 5 by a belt 45, and the driving belt 11, loosened or disconnected, it is ready for operation.

If the motor is connected to a suitable source of current supply, and the treadle 7 is moved to pull the chain 20 downward, the slide 17 is moved downward, guided by the 30 pin 38. This motion of slide 17 first changes the angle of pull on spring 43 so that the switch arm is rotated on the pin 38 from the position shown in Fig. 2 to the position in which the contacts 40 are connected together 35 by the contact 41 to complete the motor circuit. The motor being a series motor, immediately exerts its maximum torque, but the pressure between the friction plates of brake 40 has not been appreciably relieved and consequently the motor is prevented from rotating. Further motion of the treadle 7 to pull the chain 20 farther downward, moves the slide so that the pin 35 on the brake lever 18 is engaged by the end of the slot 36 in 45 the slide 17, whereby the brake lever is rocked on its pivot and the spring 22 is compressed. This relieves the pressure between the friction plates and the motor begins to rotate, rotating the pulley 44 and through 50 the belt 45, the fly-wheel 5, which in this case acts as the driving wheel of the machine. If the spring 22 is only partially compressed, the pressure between the friction plates is only partially reduced, and the motor and 55 machine run at minimum speed. If the spring 22 is compressed so as to gradually relieve the pressure between the friction plates, the braking effect on the motor is gradually reduced, permitting a gradual increase in speed until maximum speed is 60 reached.

When the treadle is rocked back, the spring 23 gradually moves slide 17 upward toward the position shown in the drawings, 65 the spring 22 pressing brake lever 18 against

friction plate 30 and gradually increasing the friction between friction plates 25 and friction plates 27 and 28, thereby causing a gradual reduction in speed of the machine and motor until the motor is finally brought 70 to a standstill. The spring 23 then moves slide 17 so as to change the angle of pull of spring 43, and causes it to move switch arm 42 into the position in which the circuit between contacts 40 is opened. The lower ends 75 of the slots 37 and 36 in the slide in this position engage the pins 38 and 35, respectively. The slide is shown as being provided with suitable stop pins 46 and 47 for bringing the slide into positive engagement with 80 the switch lever 42 when in either of its extreme positions.

I desire it to be understood that my invention is not limited to the particular arrangement shown and described and I aim in the 85 appended claims to cover all modifications which do not depart from the spirit and scope of my invention.

What I claim as new and desire to secure by Letters Patent of the United States, is:— 90

1. The combination with a machine to be driven, of an electric motor adapted to drive the same, and means for controlling said motor comprising a switch for the motor supply circuit, a friction brake for said 95 motor, a brake lever operatively connected with said brake, a slide having a slot and pin connection with the motor frame and operatively connected with said switch and said brake lever, said slide being adapted to move 100 in a substantially straight line, and means for actuating said slide to close said switch and progressively release said brake.

2. The combination with a machine to be driven, of an electric motor adapted to drive 105 the same, and means for controlling said motor comprising a switch for the motor supply circuit, a slide having a slot and pin connection with the motor frame and being operatively connected with said switch, a 110 friction brake for said motor, a brake lever pivotally mounted on the motor frame and operatively connected with said brake, said brake lever having a slot and pin connection with said slide, and means for actuating said 115 slide to close said switch and progressively release said brake.

3. The combination with a machine to be driven, of an electric motor adapted to drive 120 the same, and means for controlling said motor comprising a switch for the motor supply circuit, a friction brake for said motor, a brake lever operatively connected with said brake, a slide having a slot and pin connection with the motor frame and operatively connected with said switch and said 125 brake lever, means for actuating said slide to close said switch and progressively release said brake, spring means engaging said brake lever for normally applying said, 130

- brake, and other spring means operatively associated with said slide for normally maintaining the slide in the position in which the switch is open and the brake applied.
4. The combination with a machine to be driven, of an electric motor adapted to drive the same, and means for controlling said motor comprising a switch for the motor supply circuit, a slide having a slot and pin connection with the motor frame and being operatively connected with said switch, a friction brake for said motor, a brake lever pivotally mounted on the motor frame and operatively connected with said brake, said brake lever having a slot and pin connection with said slide, means for actuating said slide to close said switch and progressively release said brake, spring means engaging said brake lever for normally applying said brake, and other spring means operatively associated with said slide for normally maintaining the slide in the position in which the switch is open and the brake applied.
5. The combination with a machine to be driven, of an electric motor adapted to drive the same, and means for controlling said motor comprising a switch for the motor supply circuit, a slide having a slot and pin connection with the motor frame and being operatively connected with said switch, stationary and rotatable friction plates surrounding the motor shaft, a brake lever pivotally mounted on the frame of said motor and operatively connected with said friction plates, said brake lever having a slot and pin connection with said slide, means for actuating said slide to close said switch and progressively release said brake, spring means engaging said brake lever for normally applying said brake, and other spring means having one end attached to said slide and the other end attached to the motor frame for normally maintaining the slide in the position in which the switch is open and the brake applied.
6. The combination with a machine to be driven, of an electric motor adapted to drive the same, and means for controlling said motor comprising a switch for the motor supply circuit, stationary and rotatable friction plates surrounding the motor shaft, a slide having a slot and pin connection with the motor frame and being operatively connected with said switch, a brake lever pivotally mounted on the motor frame and having a bifurcated end straddling the motor shaft, said bifurcated end engaging one of the stationary friction plates, the other end of said brake lever having a slot and pin connection with said slide, means for actuating said slide to close said switch and progressively release said brake, spring means engaging said brake lever for normally maintaining said friction plates in engagement with each other, and other spring means operatively associated with said slide and normally maintaining said slide in the position in which the switch is open and the brake applied.
7. The combination with a machine to be driven, of an electric motor adapted to drive the same, and means for controlling said motor comprising a switch for the motor supply circuit, a friction brake for said motor, a brake lever pivotally mounted on the motor frame and operatively connected with said brake, a slide having a slot and pin connection with the motor frame and being operatively connected with said switch and said brake lever, means for actuating said slide to close said switch and progressively release said brake, spring means engaging said brake lever for normally applying said brake, and other spring means having one end attached to said slide and the other end attached to the motor frame for normally maintaining the slide in the position in which the switch is open and the brake applied.

In witness whereof, I have hereunto set my hand this 30th day of August 1915.

JAMES J. WOOD.
